UNITED STATES PATENT OFFICE.

ALBERT F. MILLER, OF DENVER, COLORADO.

MECHANICAL-MOVEMENT MECHANISM.

1,223,509.

Specification of Letters Patent.

Patented Apr. 24, 1917.

Application filed April 28, 1916. Serial No. 94,211.

To all whom it may concern:

Be it known that I, ALBERT F. MILLER, a citizen of the United States of America, residing in the city and county of Denver and State of Colorado, have invented a new and useful Mechanical-Movement Mechanism, of which the following is a specification.

My invention relates to a new mechanical movement; and the objects of my invention 10 are:

First, to provide a mechanical movement by which two oppositely positioned slidingly arranged members which may be adapted to perform various functions in 15 various ways and in different machines, may be made to have a joint simultaneous movement toward a center line or point centrally located between them, from which they are equi-distantly placed, and may be jointly 20 moved and secured in adjusted positions at any predetermined distance from said center line within the lengths of their sliding movement toward or away from said center line, and at the same time both of said members have an intermittent reciprocal simultaneously operating stroke movement toward or away from said center line or point 25 of a predetermined stroke movement. And

Second, to provide a simple, automatically operating reciprocal movement mechanism by which two heads or other members may be automatically reciprocated toward and away from each other intermittently through any desired predetermined reciprocal stroke, and still be moved and set farther apart or nearer together without interfering with their intermittent reciprocal movement.

I attain these objects by the mechanism 40 illustrated in the accompanying drawings, in which:

Figure 1 is a transverse vertical sectional view through a box wrapping machine, illustrating the application of the mechanism 45 for affecting a mechanical movement.

Fig. 2 is an enlarged front view of one of the sliding members illustrated in Fig. 1 and showing in cross section the main feed screw for operating the head blocks, the 50 square rod passing loosely through a plug threaded to said blocks and a follower which connects the threaded rods and the said plug, and

Fig. 3 is a horizontal sectional view on the line 3—3 of Fig. 2.

55

Similar letters of reference refer to similar parts throughout the several views.

Referring to the drawings,—

Fig. 1 designates a mechanical movement embodying my invention. In order to 60 illustrate my mechanical movement performing an automatically operating intermittent reciprocal function, and at the same time arranged to move two members toward or away from each other, I have preferred 65 to illustrate it operatively connected to two operating chuck heads which are used to perform a blank wrapping turning-in function in a box wrapping machine, although my invention contemplates broadly the application of my mechanical movement to any machine or to any operative mechanism 70 of any kind or character requiring lateral reciprocal stroke movement in conjunction with a variable distance movement between 75 the operative function performing mechanism.

The application of my invention to the side turn-in mechanism of a box wrapping machine such as is illustrated in the pending 80 application Serial Number 3447 filed May 25, 1915, involves all of the principles of my invention in such a clear and comprehensive manner that they can be readily understood.

In the drawing, the numeral 1 designates 85 a flat smooth top table, which is preferably provided with two side frames 2 and 3, which are secured to a lease plate 4, along which a shaft 5 is rotatably mounted in suitable bearings 6, which shaft is rotated by 90 any suitable power transmitting belt or gearing mechanism which is connected to it but which I do not illustrate. Upon this shaft I mount a cam disk 7, which cam disk engages a roller 8 on one arm 9 of a double 95 crank lever that is supported in a bracket 10 that is bolted to the bed plate of the machine.

The other arm 11 connects with the lower end of a connecting rod 12, the upper end 100 of which is pivotally attached to a lever 13 which is mounted on the adjacent end of a square shaft 14. This square shaft is rotatably mounted in a horizontal position parallel to the top flat surface of the table and 105 at right angles to the length of the table.

The bearings in which the square shaft is mounted will be presently described.

To the top of the table on opposite sides of its longitudinal center and at equal distances from it, we secure the two head blocks

5 A and B, which support the side turn-in mechanisms of a box wrapping machine. The side turn-in mechanisms of these two head blocks face each other and as they are 10 exactly alike a description of one will suffice for both, and inasmuch as they illustrate the action of my present invention, I deem it advisable to describe them.

Each head block consists of a base portion 15 that is slidably mounted to be moved in a horizontal plane in a transverse slideway 16 formed in the table, and a vertically movable chuck block 17 that is vertically adjustable upon upwardly projecting standards 18 that are formed on the base 15. The standards are yoke-shaped and are provided with guide ways and each chuck block is provided with a cap lugged portion 19 that is slidably mounted in the guide way 20 of the standard. A threaded rod 20 is rotatably mounted at its upper end in a bushing 21 at the top of the standard and threads down through the lug 19 of the chuck block, its lower end resting in a bearing in the adjacent end of the base 15. The threaded rod is adapted to receive a wrench to turn it to raise or lower the chuck block which has a vertical movement on the standard sufficient to allow it to be adjusted to 35 all heights or depths of boxes the machine will wrap. This chuck block extends down through a slot in the table, when adjusted for boxes of slight depth, and it is adjustably movable up and down to accommodate 40 boxes of different depths, and is fixed in adjusted positions by its cap 22 which can be clamped tightly to the standards. The chucks face the opposite sides of the box that is to be wrapped (see Fig. 1), and the 45 opposing side members of each chuck are each provided with a semi-circular slideway 23, and in each pair of slideways is mounted a segmental block 24, which therefore travels in a semi-circular path and is 50 moved in this path by a combination of link and lever members, which are constructed and act as follows:

The segment block is provided with a depending bifurcated lug 25, to which one end 55 of a link 26 is pivoted. The lower end of this link is provided with an oblong slot and is pivotally connected through this slot by a pin to the upper end of a vertically reciprocable bar 27, which is slidably mounted in a guide 28 that is formed on a depending portion of the head block, which is given a vertical reciprocating movement by a mechanism which I do not illustrate.

Along the front face of each chuck I 65 secure a bar 29, against which the upper edges

of the sides of the boxes bear, when the turn-in blades bend the extended portions of the sides of the blank over against the inner faces of the sides of the box, as shown in Fig. 1.

One side of the depending portion 30 of the head block is provided with an opening, in which is secured an internally threaded bushing 31, in which is screwed a plug 32, having a square hole, the outer end of the 75 plug having an annular groove 33. Through these plugs passes the square rod 14, the ends of which are rounded and enter bushings in the sides of the table. A right and left hand threaded rod 34 extends parallel with and adjacent to the square rod 14, and upon the end portions of the threaded rod are screwed followers, comprising hub members 35 having arms 36, the outer ends of which are bifurcated, and straddle the annularly grooved ends of the plugs 32. Thus by turning the crank handle 37 on the end of the threaded rod 34, the said rod is rotated, and the head blocks are moved inward or outward in their slideways 16. The 80 object of threading the plugs to the bushings 31 is as follows: When the boxes pass from the first into the second stage position, the head blocks stand in such positions relatively to each other that the boxes may 85 pass readily between the bars 29 without touching them, but after they have reached their proper position, it is necessary that their sides should be engaged by the said bars 29, and to accomplish this a slight inward movement is given to each head block, by turning the square rod by which the 90 plugs 32 are turned, and as the plugs when turned by the square rod are held against lateral movement by the followers 36, the 95 head blocks are thereby moved in or out according to the direction of rotation of the 100 plugs. The square rod is turned in the following manner: The cam disk 7 and its cam 7^A engage the roller 8 on the member 105 9 of the double crank arm. The other arm 11 operates the connecting rod 12, which 110 operates the lever 13, and the shaft 14 is thereby turned, and the desired variable reciprocal stroke can be given to the heads 115 by providing cams with different predetermined throw movements.

The operation of this turn-in mechanism has nothing to do with the mechanism of my present invention that moves the chuck heads toward each other automatically and 120 grips the box between them as each box is fed between them, and then backs off to release the box and to receive another one; the above chuck turn-in mechanism shows however, that my mechanism can be reliably used to operate complicated mechanism that necessarily has to work with timed precision and certainty of positive action. At the 125 same time by applying the hand crank to the 130

screw 34, the chuck heads can be quickly moved together or separate and set in exact positions on each side of the center to receive either larger or smaller boxes.

5 My invention provides a mechanical center distance varying and reciprocal stroke mechanism that can be adapted to a wide range of uses in machines designed for different purposes, and while I have illustrated 10 and described the preferred construction and arrangement of my invention, I do not wish to be limited to it, as many changes might be made without departing from the spirit of my invention.

15 Having described my invention, what I claim as new and desire to secure by Letters Patent, is:

1. A mechanical movement comprising oppositely facing sliding members, means 20 including a power actuated rod for reciprocally moving said sliding members, and means including a threaded rod operatively connected to said power actuated rod and to said sliding members for moving said sliding members toward or away from each other without interfering with their regular cam actuated reciprocating movement.

2. In a mechanical movement, the combination of a supporting table, having oppositely arranged function performing heads, with a square rod connected to said heads, and means including a cam actuated mechanism for operating said square rod to reciprocate said heads simultaneously toward and 35 away from each other.

3. In a mechanical movement, the combination of a table provided with oppositely arranged slideways, head members slidably mounted in said slideways, a manually operated threaded rod rotatably mounted in said table, means operated by the threaded rod for moving said head members, and means including cam actuated mechanism for reciprocating said heads in their slideways independent of their reciprocal movement by said threaded rod.

4. The combination in a mechanical movement of a table provided with oppositely arranged slideways, heads slidably mounted therein, with a square rod rotatably journaled at its ends to said table, and means including threaded plugs surrounding slidably the opposite end portions of said rod, a bushing secured to each head and threaded over each of said threaded plugs, a threaded shaft mounted in said table parallel with the square rod, and means including cross levers threaded to said rods having bifurcated ends which engage grooves in the ends of 55 said threaded plugs.

5. In a mechanical movement the combination of a table provided with oppositely arranged slideways, heads slidably mounted therein, with a square rod rotatably journaled at its ends to said table, means includ-

ing threaded plugs surrounding slidably the opposite end portions of said rod, a bushing secured to each head and threaded over each of said threaded plugs, means including cross levers supported by said table and in 70 which said plugs are turnable for preventing said plugs from moving laterally on said square rod, and means including cam actuated mechanism for turning said square rod to impart a power actuated reciprocating 75 movement to said heads of any predetermined stroke simultaneously toward and away from each other.

6. The combination in a mechanical movement of a table provided with oppositely arranged slideways, heads slidably mounted therein, with a square rod rotatably journaled at its ends in said table, means including threaded plugs surrounding slidably the opposite end portions of said rod, a bushing secured to each head and threaded over each of said threaded plugs, means including cross levers supported by said table and in 80 which said plugs are turnable for preventing said plugs from moving laterally on said square rod, a lever secured at one end to said square rod a connecting rod 85 pivotally connected to the opposite end of said lever and means including a cam actuated rock arm for reciprocating said connecting rod to partially turn said square shaft whereby said heads are reciprocally moved in unison toward and away from each other with a continuous alternating reciprocal movement of predetermined stroke. 100

7. The combination in a mechanical movement of a table provided with oppositely arranged slideways, heads slidably mounted therein, with a square rod rotatably journaled at its ends to said table, means including threaded plugs surrounding slidably the opposite end portions of said rod, a bushing secured to each head and threaded over each of said threaded plugs, said plugs being provided with an annular groove, a follower 110 mounted loosely at one end in each annular groove, a threaded rod rotatably secured to said table and threaded to the opposite ends of said followers, and means including a crank for manually turning said threaded 115 rod whereby said heads may be moved toward or away from each other simultaneously and in unison independent of their power driven intermittent reciprocal movement. 120

8. The combination with a table having oppositely arranged head-blocks slidably mounted therein, of aligned plugs in threaded engagement with said heads, having square axial apertures and annularly grooved at 125 their outer ends, a square rod mounted at its ends in said table and passing loosely through said plugs, a manually operated right and left hand threaded rod extending parallel with the square rod and mounted at 130

its ends in said table, followers in threaded engagement with said threaded rod and having bifurcated ends which engage the grooved ends of said plugs, and means for 5 imparting a partial rotation to said square rod.

9. In a device of the character described, the combination with a table having oppositely arranged head blocks slidably mounted 10 therein, of means for moving said blocks simultaneously toward or away from each other, and means connected with head block moving means, but having an independent action therefrom, for imparting short reciprocating movements to said blocks independently of the first mentioned moving means.

10. The combination with a support and 20 opposite head blocks slidably mounted therein, of plugs in threaded engagement with said blocks, having square axial apertures

and annularly grooved outer ends, a square rod rotatably mounted at its ends in said support and passing through said plugs, an arm on said square rod, a double-armed rock 25 lever, a rod connected to the arm on said shaft and one arm of said rock lever, a roller on the other member of said rock lever, and a cam for engaging said roller thereby to rock said double armed lever, a manually 30 operated right and left hand threaded rod extending parallel with the square rod and mounted at its ends in said support, and followers threaded to said threaded rod and having bifurcated ends which engage the 35 grooved ends of said plugs.

In testimony whereof I affix my signature in presence of two witnesses.

ALBERT F. MILLER.
